RALPH A. HAMANN, OF OMAHA, NEBRASKA.

RECTIFIER.

1,014,466.

Specification of Letters Patent.

Patented Jan. 9, 1912.

Application filed February 17, 1909. Serial No. 478,402.

To all whom it may concern:

Be it known that I, RALPH A. HAMANN, a citizen of the United States, and a resident of Omaha, in the county of Douglas and 5 State of Nebraska, have invented a new and Improved Rectifier, of which the following is a full, clear, and exact description.

My invention relates to rectifiers for alternating currents, my more particular purpose being to arrange one or more polarized relays in such manner that when energized by aid of an alternating current, the relay or relays shift the direction of the currents at the proper moment to take advantage of 10 the direction of the current and thus to selectively build up one or more currents of unitary direction.

More particularly stated, I arrange the polarized relay or relays in such manner 20 that the armature or armatures thereof by being shifted bodily back and forth with a frequency of movement corresponding to the frequency of the alternating current, cause different phases of the alternating 25 current to pursue different paths.

Reference is to be had to the accompanying drawings forming a part of this specification, in which similar characters of reference indicate corresponding parts in all 30 the figures.

Figure 1 is a diagram showing a form of my invention in which there are two mains for alternating currents and two wires for direct current, there being thus provided two 35 taps for the direct current, this system being suitable for a low voltage; Fig. 2 is a diagram of another form of my invention, there being in this instance two polarized relays each provided with its own armature, 40 the parts being arranged for producing direct currents of a very high voltage; and Fig. 3 shows still another form of my invention, the construction in this figure being somewhat simpler than that shown in 45 Fig. 2 yet retaining many of its advantages.

The mechanism shown in Fig. 1 will first be described. At 4, 5, are alternating current mains, and connected with the same are conductors 6, 7. At 8 is a polarized electro-magnet which is connected by a wire 9 which is connected to a condenser 10, the latter being connected by a wire 11 with the conductor 6. The polarized electro-magnet 50 8 is connected by a wire 12 with another polarized electro-magnet 13 and the latter is connected with a resistance 4, the resist-

ance in turn being connected with the conductor 7. A wire 15 is connected with this last-named conductor and is also connected with a movable armature 16. The two magnets 8, 13 and the movable tongue 16 together constitute a polarized relay; that is, a relay in which the magnet cores are of steel and permanently magnetized. The tongue 16 is so polarized as to be normally 60 attracted by one magnet 8 or 13 (it matters not which) and repelled by the other. For convenience it may be assumed that when the device is idle, the armature 16 rests against the contact point 18. Connected 65 with the contact points 17, 18 are direct current wires 19, 20. Two other direct current wires 21, 22 are connected to a wire 23 which leads to the conductor 6. The capacity of the condenser 10 is so proportioned that the 70 alternating current working through this capacity, the polar relay associated with it, and the resistance 4, is sufficient to operate the relay and cause the armature to vibrate first to the right and then to the left, so 75 as to engage and disengage the contact points 17 and 18. The resistance 4 and the capacity of the condenser 10 are so proportioned as to maintain a certain degree of 80 lead in the alternating current as regards 85 its action upon the polarized magnets 8, 13. This is for the purpose of maintaining the current a little in advance of the electromotive force energizing the polarized magnets. By this means the armature 16 is moved 90 slightly before the full effect of the current takes place in the mains. The condenser 10 is adjustable for the purpose of adjusting the lead and thus keeping the instrument in proper phase relation to the currents energizing the mains. Two direct current motors, 24, 25, of a kind suitable for direct 95 current, are in this instance used, connected with the direct current wires 19, 21, or 20, 22.

The operation of the mechanism shown in Fig. 1, is as follows: I will suppose that at a particular instant, the main 4 and conductor 6 are charged positively, and at the same instant the main 5 and conductor 7 are charged negatively, so that for this instant 105 current tends to flow from the right to the left according to Fig. 1. As the condenser 10 allows a momentary current to pass, the polarized magnets 8, 13, are energized, and the armature 16 is moved to the right so as 110 to engage the contact point 17. The circuit for this purpose is as follows: main 4, con-

ductor 6, wire 11, condenser 10, wire 9, polarized magnet 8, wire 12, polarized magnet 13, resistance coil 14, conductor 7, main 5, to power house, thence back to main 4. The 5 polarized magnets 8, 13, having been thus energized, and the armature 16 being in engagement with the contact point 17, as stated, and current being unable to pass the condenser 10 in any appreciable quantity, 10 the circuit is completed as follows: main 4, conductor 6, wire 23, wire 21, motor 24, wire 19, contact member 17, armature 16, wire 15, conductor 7, main 5, to power house, thence to main 4. The current thus flows 15 through the wire 19 in a direction corresponding to that just followed in tracing the circuit. The alternating current now reverses its direction, the polarized magnets being energized with opposite polarities, 20 and the armatures being moved to the left so as to disengage the contact member 12 and to engage the contact member 18. The current now flows through the following circuit: main 5, (for instance, not 4) conductor 7, wire 15, armature 16, contact member 25 18, wire 20, motor 25, wire 22, wire 23, conductor 6, main 4, to power house, thence back to main 5. The current flowing through the wires 20, 22, is in an opposite 30 direction from that which flowed just before through wires 19, 21. The alternating current now again reverses, so that a second current is sent through the wires 19, 21, in the same direction as the current first 35 energized in these wires. Another reversal of the alternating current, and another pulsation is sent through the wires 20, 22, the direction of this pulsation being the same as that of the first pulsation which energized these particular wires. The net result 40 is that the wires 19, 21 when energized at all, are always energized in the same sense, that is, by currents having always the same direction. The wires 20, 22 when energized 45 at all, are likewise always energized in the same sense, that is, by currents having a unitary direction, yet the direction of the currents energizing the wires 19, 21, is always contrary to the direction of the currents 50 energizing the wires 20, 22. If any current be drawn from the wires 19, 21, or from the wires 20, 22, such currents will always necessarily have the same direction.

In the form shown in Fig. 3, the general 55 principle is much the same, but the mechanism shown in Fig. 2 is more particularly adapted for currents of high voltage. At 26, 27, are shown alternating current mains which are connected with conductors 28, 29. 60 At 30, 31, are polarized magnets which are connected together by a wire 32. Disposed intermediate these magnets is a polarized armature 33 which plays back and forth and makes and breaks engagement with stationary contact points 34, 35. A wire 36 is con-

nected with the polarized magnet 31 and with the conductor 29. The wire 37 is connected with the conductor 28 and with the polarized magnet 38. Another polarized magnet 39 is disposed adjacent to the polarized magnet 38, these two magnets being connected by a wire 40. An armature 41 is disposed intermediate the polarized magnets 38, 39, and is connected by a wire 42 with the conductor 29. Contact points 43, 75 44, are disposed upon opposite sides of the armature 41, and are engaged and disengaged by this armature as the latter swings back and forth. A wire 45 is connected with the polarized magnet 39 and with the 80 condenser 46. Disposed intermediate this condenser and the conductor 29 is a resistance 47. The contact point 43 is connected by wires 48, 49 with the contact point 35; a wire 50 is connected with the wires 48, 49. 85 A wire 51 is connected with the contact point 44 and is also connected to a wire 52 which leads to the contact point 34. A wire 53 is connected with the wires 51, 52. A wire 54 is connected with the polarized magnet 30 90 and with a condenser 55, and a resistance 56 is disposed intermediate this condenser and the conductor 28. A direct current motor 53a is connected with the wires 50, 53. A wire 57 is connected with the armature 33 95 and with the conductor 28.

The operation of the device shown in Fig. 2 is as follows: Suppose as before, that the line is in such condition that a current tends to flow from the main 26 and conductor 28 100 to the left according to Fig. 2, that is, toward the conductor 29 and main 27. The polarized magnets 30, 31, 38, 39 are energized without any material waste of current. This is by virtue of the condensers 46, 105 55, which permit the passage of just enough current to energize the polar relays to that degree necessary to move the armatures 33, 41 to the right according to Fig. 2. The armature in question being thus moved, the 110 following circuit is completed: main 26, conductor 28, wire 57, armature 33, contact point 34, wire 52, wire 53, to instrument, line, or circuit through which the direct current is to be sent; next, wire 50, wire 48, contact point 43, armature 41, wire 42, conductor 29, main 27, to power house, thence back to main 26. A current is thus sent 115 through the wires 50, 53 and motor 53a in one direction. The direction of the alternating current being now reversed so that the armatures 41, 33 are thrown to the left according to Fig. 1, the current flows through the system, pursuing the following circuit: main 27 (not 26), conductor 29, 120 wire 42, armature 41, contact point 44, wire 51, wire 53, motor 53a (same direction as before), wire 50, (same direction as before), wire 49, contact point 35, armature 33, wire 57, conductor 28, main 26, to power house,

thence back to main 27. The currents flowing through the wires 50, 53 also have by this arrangement the same direction, and may therefore be considered as direct, 5 though perhaps discontinuous currents.

In the form shown in Fig. 3, the alternating mains appear at 58, 59, and communicate with the conductors 60, 61. At 62, 63 are polarized magnets connected together by 10 a wire 64. A polarized armature 65 is associated with the magnets 62, 63, and swings to the right or left, according to the changing direction of the currents used for energizing these magnets. Mounted upon the 15 armature 65 and insulated therefrom and from each other are two tongues 66, 67. Connected with these tongues, respectively, are spiral metallic springs 68, 69 of conducting material, these springs being connected 20 with wires 70, 71, so as to maintain the tongues 66, 67 respectively in communication with the conductors 60, 61. A wire 72 is connected with the polarized magnet 62, and this wire is also connected with a variable 25 condenser 73. A wire 74 is connected with this condenser and with the conductor 60. A resistance 75 is connected with the conductor 61 and with the polar magnet 63. Contact points 76, 77 are disposed upon opposite 30 sides of the tongue 66. Other contact points 78, 79 are disposed upon opposite sides of the tongue 67. A wire 80 is connected with the contact point 76 and with the wire 81 which leads to the contact point 35 79. A wire 82 is connected with the wires 80, 81. A wire 83 is connected with the contact point 78, and another wire 84 which leads to the contact point 77. A wire 85 is connected with the wires 83, 84. At 83^a is 40 a direct current motor, to be driven by the verified current.

The operation of the form shown in Fig. 3 may be readily understood from the foregoing description regarding the other views. 45 The condenser 73 being properly adjusted, and the polarized magnets 62, 63 being energized so as to move the armature 65 to the right, the tongue 66 is brought into engagement with the contact point 76, while the 50 tongue 67 engages the contact point 78. The current can now flow through the following circuit: main 58, conductor 60, wire 70, wire spring 68, tongue 66, contact point 76, wire 80, wire 82, (instrument, circuit or 55 line to be energized), wire 85, wire 83, contact 78, tongue 67, wire 69, wire 71, conductor 61, main 51, to power house, thence back to main 58. The direction of the alternating current being now reversed, the 60 magnets 62, 63, are again energized, but in the opposite sense. The armature 65 is thrown to the left, and the following circuit is completed: main 59 (not 58), conductor 61, wire 71, wire 69, tongue 67, contact point 65 79, wire 81, wire 82 (same direction as be-

fore), motor 82^a, wire 85 (same direction as before), wire 84, contact point 77, tongue 66, wire 68, wire 70, conductor 60, main 58, to power house, thence back to main 59. The current flowing through the wires 82 and 70 85 and such instrument, circuit or line as may be connected therewith, thus always flows in the same direction.

In all three of the forms above described the condenser eliminates excessive sparking 75 and preserves the contact surfaces. By adjusting the variable condenser at will, the sparking may be reduced to such an extent that it becomes nil even where currents of considerable amperage and high voltage are 80 employed. When the condenser is properly adjusted the armature of the polar relay allows its contacts to break and make while the current is at zero, thus doing away with 85 sparking at points and also allowing the full half cycle to pass through.

In all three of the forms described, it is an easy matter to make the armature or armatures of the polar relay sufficiently delicate to be actuated quickly enough to respond to the frequency of the alternations. 90 Indeed, in most commercial circuits, there are seldom more than 110 alternations per second, and a vibratory tongue can be readily made to perform 110 movements per 95 second. The frequency may in fact be considerably higher than 110 per second, without any danger of the armature being too slow.

I do not limit myself to the precise form 100 of magnets shown, for the reason that magnetic members of other types may in some instances be deemed preferable. Neither do I in all cases limit myself to a polar relay or even to polarized magnets, the scope 105 of my invention being commensurate with my claims.

Having thus described my invention, I claim as new and desire to secure by Letters Patent:

110

1. In a rectifier for alternating currents, the combination of alternating current mains, a polarized relay provided with a movable armature and with magnetic members, a variable condenser, said magnetic 115 members and said variable condenser being bridged across from one of said mains to the other for the purpose of enabling said magnetic member to be energized by alternating currents flowing into and out of said 120 condenser, stationary contact members mounted upon opposite sides of said movable armature, and translating devices connected with said contact members and with one of said alternating current mains. 125

2. In a rectifier for alternating currents, the combination of alternating current mains, a polarized relay provided with a movable armature and with magnetic members, a variable condenser, said magnetic 130

members and said variable condenser being bridged across from one of said mains to the other for the purpose of enabling said magnetic members to be energized by alternating currents flowing into and out of said condenser, stationary contact members to be energized and deenergized by movements of said armature, and translating devices connected with said contact members and energized by currents flowing through said con-

tact members and through said alternating current mains.

In testimony whereof I have signed my name to this specification in the presence of two subscribing witnesses.

RALPH A. HAMANN.
